UNITED STATES PATENT OFFICE.

PEYTON CASSNER, OF GOULD, KANSAS.

VENTILATOR.

SPECIFICATION forming part of Letters Patent No. 268,183, dated November 28, 1882.

Application filed April 4, 1882. (No model.)

To all whom it may concern:

Be it known that I, PEYTON CASSNER, a citizen of the United States, residing at Gould, in the county of Greenwood and State of Kansas, have invented certain new and useful Improvements in Ventilators, of which the following is a specification, reference being had therein to the accompanying drawings.

My invention relates to a certain improvement in means for the ventilation of rooms, in connection with a stove-pipe or smoke-flue, and is hereinafter first described, and then designated in the claim.

In the drawings hereto annexed, Figure 1 shows my invention as applied to an ordinary stove-pipe in a house. Figs. 2, 3, 4, and 5 are views showing the parts in detail.

The letter A designates the floors of the house; B, the stove; C, the stove-pipe, from 20 under the hood C' of which the smoke issues, as indicated by the arrows. The smoke-pipe, of course, is continuous from the stove to the said hood. Surrounding the smoke-pipe is a larger pipe, D, the intervening space, e, in which 25 serves as the ventilator-flue. Suitable provision is made to secure the smoke-pipe in the center of the ventilating-flue, or, in other words, to secure an intervening space about the smoke-pipe of equal dimension all around.

30 This is effected by the angular bent strips f, of sheet metal, attached to the smoke-pipe by rivets f', as seen in Fig. 5. These strips bend outward or away from the smoke-pipe far enough to serve as stays to rest against the 35 inner-side of the wall of the ventilating-flue, and when three or four of these stay-strips are thus secured about the smoke-pipe at a given point they will insure that the intervening space shall be of equal dimension all around.

40 It is important that the device f to equalize the dimension of the surrounding space shall be attached, as shown, to the smoke-pipe only, as thereby the two pipes may be readily separated and taken down when it is necessary to 45 clean the smoke-pipe of soot. As indicated in Fig. 4, these stay-strips are secured to the pipe at suitable intervals throughout its length. Instead of the stay-strips to effect the equal 50 dimension of the intervening space, a perforated ring-shaped diaphragm of sheet metal may be used, the same to be placed around the

smoke-pipe and between it and the ventilating-flue.

In the lower room, or where the apparatus is used in a house of but one story, the lower 55 end, g, of the ventilating-flue—that is, the intervening—may be open for the admission of vitiated air, as indicated in Fig. 1 by the arrows. This open end should be near the ceiling of the room. In the case of an upper room, 60 or where the same flue extends through more than one story, provision is made for the admission of the vitiated air by forming holes h in the wall of the flue. These holes are placed only near the ceiling, as shown, and the air of 65 the room finds entrance to the intervening space, e, through said holes. The extreme upper end of the ventilating-flue is covered by a downward-flaring collar or cap, D', the small upper end of which fits closely about the smoke- 70 pipe, while the downflaring part sets over and rests upon the upper end, i, of the flue, (see Fig. 5,) and thus serves to prevent rain or snow from entering the intervening space. Outlet-holes n are made in the extreme upper end of 75 the vent-flue for the escape of the vitiated air. It is immaterial as to what shape these outlets have. They may be holes in the wall of the flue, as shown, or the upper end of said flue may be notched, so that while the air may find 80 outlet through the notches the downflaring collar may set upon the metal between the notches. To afford protection to these outlets in the vent-flue, the downflaring collar is provided with a depending flange, p, which forms 85 a guard around the air-outlets. By this arrangement the air from the intervening space escapes through the outlets n under the downflaring collar, and thence passes out from under the depending flange p. 90

Figs. 2 and 5 show the upper end, g, of the smoke-pipe. The hood C' is attached to a short section of pipe, r, which sets down over and around the said upper end of the smoke-pipe, and the lower edge of the short section 95 r rests upon the small upper end of the flaring collar D', as shown in Fig. 5. Thereby all the parts are so tightly fitted as to exclude rain or snow.

Should it be desired to use a stove in an upper room where the vent-flue and smoke-pipe extend from a lower room through the floor to 100

the upper story, as shown in Fig. 1, the smoke-pipe of the stove in said upper room must pass into the vent-flue and connect, as shown at S, to the smoke-pipe from the lower room.

5 From the foregoing description the operation is obvious. First, the heat of the smoke-pipe induces an upward draft in the intervening space, which insures the escape of the vitiated air, and the construction of the parts at 10 the upper end of the smoke-pipe and vent-flue is such as to insure a tight fit and thoroughly exclude the rain or snow.

I am aware that a double tube with a space between has been employed for ventilating 15 buildings—as, for instance, that shown in United States Patent No. 142,598, dated September 9, 1873—and such I do not claim broadly.

Having described my invention, I claim and 20 desire to secure by Letters Patent of the United States—

A combined smoke-pipe and ventilator consisting of a smoke-pipe, C, a larger pipe, D, around the smoke-pipe, space-equalizing device f, attached to the smoke-pipe, a down-flaring collar, D', covering the upper end of the large pipe and fitting closely around the smoke-pipe, outlets from the large pipe, just below the collar, a short section of pipe, r, around the upper end of the smoke-pipe and 30 having its lower edge resting upon the flaring collar, and a hood, C', attached to the upper end of the short section, whereby while the pipes may be readily separated all the parts are so tightly fitted together as to exclude rain, 35 as set forth.

In testimony whereof I affix my signature in presence of two witnesses.

PEYTON CASSNER.
